UNITED STATES PATENT OFFICE.

JESSE E. LANGSDORF, OF NEW YORK, N. Y.

NECKTIE.

Application filed June 30, 1922. Serial No. 571,903.

To all whom it may concern:

Be it known that I, JESSE E. LANGSDORF, a citizen of the United States, and a resident of New York, in the county of New York 5 and State of New York, have invented certain new and useful Improvements in Neckties; and I do hereby declare the following to be a full, clear, and exact description of the invention, such as will enable others 10 skilled in the art to which it appertains to make and use the same.

This invention relates to improvements in neckties and particularly to those of the four-in-hand type.

15 It is well known that when a tie is placed between the folds of a collar and the latter is buttoned to the neck band of the shirt, it is frequently necessary prior to and during the tying operation that the tie must be 20 adjusted lengthwise in order to insure a desirable knot and to cause the tie ends to be of proper relative lengths. It has been found that the folds of the collar will tend to confine the neck portion of the tie tightly between them, so that the tie must be subjected 25 to considerable pulling strain before it can be moved. This tends to distort the tie and break the stitching which unites its folds and retains the lining in place. In many instances, the material of which body portions 30 of neckties of the four-in-hand type are made, is of a more or less elastic character and in an effort to relieve the same from being stretched, inelastic linings have been 35 employed and stitched to the folded portions of the tie, particularly throughout the neck portion thereof which passes between the folds of the collar. While such inelastic lining members have served to relieve, to some 40 extent, the stretching of the elastic body material, still it has been found that with such construction, the unequal stress upon the elastic body of the tie and the elastic lining stitched thereto, have caused the 45 stitching to break or become strained and the tie to be distorted, thus rendering it unfit for further use.

One object of my present invention is to 50 overcome the difficulties above mentioned, and to provide improved lining means for a necktie which shall be sufficiently elastic or resilient in character and stitched to the body material that breaking of the stitching or distortion of the tie when subjected to pulling 55 strain will be prevented, and at the same

time, so that said lining means shall be capable of withstanding the pulling strain after having yielded lengthwise with the body material to a limited extent.

A further object is to provide resilient 60 lining means for a tie which will yield with the body material and resume its original, normal position with the body material when pulling strain is removed, and which will operate normally to prevent slipping of the 65 tie between the folds of a collar and thus avoid accidental displacement of the tie knot.

With these and other objects in view, the invention consists in certain novel features of construction and combinations of parts as 70 hereinafter set forth and pointed out in the claims.

In the accompanying drawings; Figure 1 is a view of a tie showing an embodiment of my invention, and Figure 2 is a separate view 75 of the lining means.

The body material of the tie may be made of any suitable material,—such as silk, for example,—and the material will preferably be cut on the bias so that the body of the tie 80 will be more or less elastic in character. The body of the tie may comprise a narrow neck portion 1 and gradually widening tying ends 2 and the material is so formed as to provide folds 3 forming the inner face of the tie. 85 The folds 3 are united by loose stitching indicated at 4 and the end portions of the thread are left free near respective ends of the tie and knotted as at 6.

The loose stitching 4 which unites the 90 folds 3, also holds in place, lining means comprising two members 7 and 8, one overlying the other. These lining members may both be made of the same character of material and the material employed is such as 95 shall have a limited elastic or resilient quality such, for example, as woven fabric cut on the bias. The resilient lining members 7 and 8 may be equal in width throughout that portion of the tie which lies between the back portions of the folds of the collar, and those portions of the lining member 7 which occupies the tying ends of the tie are so formed as to provide comparatively wide ends 9, while respective end 100 portions of the lining member 8 may be tapering as indicated at 10 and underlie the gradually widening portions of the member 7.

The two resilient lining members may be 110

united by a line of loose stitching 11 extending longitudinally of the same, said stitching consisting of a single basting thread. With the use of lining means of 5 woven material having limited elasticity as heretofore described, it will stretch with the stretching of the body material and at the same time, it will not be sufficiently more elastic than the elasticity of the body material 10 as to cause breaking of the stitching, but said lining will suffice to relieve the body material from excessive stress or strain when the tie is subjected to great pulling force. It will be observed also that when 15 the tie is stretched, the loose stitching will slip and this will assist in avoiding breaking of the thread. Furthermore, by forming the intermediate portion of the elastic or resilient lining means of double thickness 20 of material, the tie will be normally held firmly between the folds of the collar and thus accidental slipping or displacement of the tie knot will be prevented.

With my improvements, distorting of the 25 tie will be prevented as the stitching will not be broken or strained when the tie is pulled and as the body material and also the lining will return to the normal positions as soon as the pulling strain shall have 30 been discontinued.

Having fully described my invention what

I claim as new and desire to secure by Letters-Patent, is:—

1. A neck-tie, comprising a body portion and lining means, the latter comprising overlying members of material having limited resilient quality and loosely stitched to the body portion of the tie. 35

2. A neck-tie, comprising a resilient body portion and resilient lining means loosely 40 stitched thereto, said lining means comprising two resilient members, the intermediate portion of one overlying the intermediate portion of the other.

3. A neck-tie, comprising a body portion 45 of resilient material and resilient lining means loosely stitched thereto, said lining means comprising two resilient members, one overlying the other, one of said members having portions gradually widening from 50 the central toward the end portions and the other lining member having tapering end portions, the intermediate overlying portions of the two lining members being substantially of equal widths. 55

In testimony whereof, I have signed this specification in the presence of two subscribing witnesses.

JESSE E. LANGSDORF.
